UNITED STATES PATENT OFFICE.

EDWARD W. BRETELL, OF NEWARK, NEW JERSEY.

TRUNK OR BOX FASTENER.

SPECIFICATION forming part of Letters Patent No. 293,279, dated May 6, 1884.

Application filed February 13, 1884. (No model.)

To all whom it may concern:

Be it known that I, EDWARD W. BRETELL, a citizen of the United States, residing at Newark, in the county of Essex and State of New Jersey, have invented certain new and useful Improvements in Trunk-Catches; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in trunk-catches to supplement a lock in securing the lid firmly to the body of the trunk; and it consists in the construction and arrangement of parts, as herein-after more fully set forth.

In the annexed drawings, which fully illustrate my invention, Figure 1 is an outside or face view of the catch, showing the same closed. Fig. 2 is an inside view, the catch being closed. Fig. 3 is a similar view, showing the catch unlocked and the tongue withdrawn from its keeper. Fig. 4 is a longitudinal central section through the upper casing, the hooked locking-lever and spring being removed therefrom. Fig. 5 is an inside view of the upper case with the locking mechanism removed. Fig. 6 shows a side and plan view of the hooked locking-lever.

To the lid of the trunk or box is fastened the upper casing, A, which is provided with a recessed tongue, D, and ears having openings for the screws or rivets which fasten said casing to the lid. The casing A is provided with an opening or slot, a, in its face, and has two lugs or studs, b c, on the inside of the cover, as shown in Fig. 5.

B is the lower casing or keeper, which is secured to the body of the trunk or box, and is provided with an opening, f, for the tongue D. It has also a catch or projection, g.

To the stud b in the recessed casing A is pivoted the locking-lever C, as shown in Figs. 2 and 3. This locking-lever C fits and plays in a recessed tongue, D, which is a downward extension of the casing A. (See Figs. 2 and 3.)

The locking-lever C is formed with an arm, d, which fits and plays in the casing A. The arm

d, which extends in an opposite direction to that of locking-lever C, has formed on it a handle or thumb-piece, e, which projects through the opening a in the casing A, by means of which the arm d and lever C can be partially rotated on the pivot b to fasten or unfasten the trunk-lid, as desired. The arm d is wide enough to entirely close or cover the opening a when the lever C is in its locked position; but when the lever C is drawn back into the tongue D by means of the handle e the slot or opening a is partially uncovered, as seen in Fig. 3. The locking-lever C is substantially a curved hook, as shown, and is above or somewhat higher than the arm d, with its hooked end fitting in and protected by the recessed tongue D, which is made shallower than the casing A proper, and rounded, so as to slide easily into the keeper B through the aperture f, as seen in Fig. 4. The recess in the tongue D is wide enough to allow the lever C to be drawn back within it when the trunk is to be opened. The tongue is open or cut away at h, to permit the hooked end of the lever C, to project and engage with the stop or catch g at the side of the opening f.

To the stud c in the casing A is attached a spring, E, one end of which bears against the casing A below the lever C, while the other end bears against a projection, i, on the hub under the lever C, as shown. This spring E serves the purpose of keeping the lever in place when in its locked position, and also when in its unlocked position, but yields when the lever is moved by means of the thumb-piece e.

From the foregoing description the operation of the device will be apparent. To fasten the trunk, the parts being in the position shown in Fig. 3, it is only necessary to lower the lid, which will cause the tongue to enter the keeper, after which the thumb-piece e is moved so as to cover the slot a, which will cause the hooked end of the lever C to engage with the catch g in the keeper, thus securely fastening the trunk. By moving the thumb-piece in the opposite direction the lever will be drawn into the tongue, thereby releasing the catch, when the lid can be raised. In case the end of the lever should be moved out of the tongue while the lid is open, no damage can be done to it, for the mere act of closing the lid will force the

projecting hook into the tongue. It will thus be seen that my invention affords a catch or fastening for trunks, boxes, &c., which is simple in construction, cheap, effective, not liable 5 to get out of order, and with the locking parts carefully concealed and protected from injury.

I am aware that latches have heretofore been made with a pair of spring-hooks pivoted in a casing and adapted to engage with socket-10 shoulders in the other part of the fastening; but this I do not claim.

Having thus described my invention, what I claim as new, and desire to secure by Letters Patent, is—

In a trunk-catch, the combination of the recessed casing A, having a slot, a, pivots b c, and recessed tongue D, provided with side opening, h, the hook or lever C, pivoted in said casing and having an arm, d, provided with thumb-piece e, the spring E, and the keeper B, having opening f and catch g, substantially as described.

In testimony whereof I affix my signature in presence of two witnesses.

EDWARD W. BRETELL.
